United States Patent Office.

HALSEY B. LUCAS, OF MIDDLETON, CONNECTICUT.

Letters Patent No. 78,216, dated May 26, 1868.

IMPROVED SKATE-FASTENING.

The Schedule referred to in these Letters Patent and making part of the same.

TO ALL WHOM IT MAY CONCERN:

Be it known that I, HALSEY B. LUCAS, of Middletown, in the county of Middlesex, and State of Connecticut, have invented a new and improved Skate-Fastening; and I do hereby declare that the following is a full, clear, and exact description thereof, reference being had to the accompanying drawings, making part of this specification, in which—

Figure 1 is a perspective view, showing a skate strapped to a boot with my improved fastening.

Figure 2 is an enlarged top view of the fastening.

Figure 3 is a sectional view of the same.

Similar letters of reference indicate corresponding parts in the several figures.

This invention relates to a new and improved device which is particularly adapted for fastening strapped skates firmly to the feet, and which is so constructed that while it will afford a leverage that will assist in tightening the skate-straps about the feet, it will also afford a firmly-holding self-locking fastening, and a shield or guard for protecting the feet from being pinched or bruised.

The nature of my invention consists in combining, with a curved shield or guard, a pivoted locking-lever and a retaining-loop, which are constructed substantially as will be hereinafter described.

To enable others skilled in the art to understand my invention, I will describe its construction and operation.

I have represented in the drawings, fig. 1, my invention applied to a skate, C, having wide heel and toe-straps applied to its foot-stand, and provided with narrow fastening-straps, in the usual well-known manner. The narrow toe-straps E of the strips D, may be fastened by means of buckles or clasps, of any suitable description, or, if desirable, my improved self-locking lever-fastenings may be applied to these toe-straps.

I have represented the improved fastening applied to the two narrow straps B G of the heel-piece A, and will now proceed to describe its construction and operation.

I first have a shield, a, which is made of a wide piece of metal properly curved, as shown in fig. 3, so as to accommodate itself to the rounded surface of the instep or upper part of the foot. In the middle of the length of this shield a are two eye-pieces d, between which a curved locking-lever, c, is pivoted by a transverse pin, e, which lever is constructed with a teat, g, upon its lower curved edge, and at a suitable distance from its pivoted end. This lever vibrates in a direction with the length of the guard or shield a, to which it is pivoted, and it is designed to serve as a self-locking lever, as will be hereinafter shown.

The shield a has an oblong slot, f, made through it, near one end, through which passes a strap, G, which strap is fastened to one of the flaps of the heel-piece A, and provided with a buckle, H, by which this strap can be shortened or lengthened at pleasure. To the opposite flap of the heel-piece A, a short strap, B, is permanently fastened, and to this strap a metal loop, b, is secured in a suitable manner, as shown in the three figures of the drawings. This loop b is constructed with one-end somewhat contracted, and with a concave seat, b', in this end for receiving the teat g, on the locking-lever c, as shown in the drawings, fig. 3.

The method of using the fastening is as follows: The shield a is drawn over the instep, and the lever c thrown back, so as to receive the loop b. The teat g on said lever is adjusted in the seat b' in the loop b, and the lever forced down in place, as shown in fig. 3, during which operation, the straps B and G will be drawn tight, and the point of contact of the loop b with the lever c will be moved so far past the centre e, that the parts will be securely locked in place, and cannot be detached until said lever is raised sufficiently to bring the teat g and its seat in the loop b above the pivot of lever c.

As this fastening is not of itself adjustable, I employ, in conjunction with it, the adjusting-strap G, by means of which the straps can be lengthened or shortened, as may be desired.

By means of the above-described fastening, I overcome many of the objections attending buckles and clasps hitherto used, and afford a powerful leverage, by which the skate-straps can be drawn very tight upon the feet, in the act of fastening them; and while this is the case, I protect the feet from being cramped by the fastening, by using a curved shield between the fastening and the boot.

This improved self-locking fastening is not only useful for skate-straps, but it can be used for hames, and other purposes.

Having described my invention, what I claim as new, and desire to secure by Letters Patent, is—

1. The heel-strap buckle for a skate, shaped to conform to the curve or instep of the foot, as shown at *a a* *g*, and constructed with the loop *b b'*, and with a curved locking-lever *c g*, all substantially in the manner and for the purpose described.
2. The two curved portions *a c*, constructed as described, in combination with the curved loop *b*, having a curved portion, *b'*, and with the adjusting-strap *B*, substantially in the manner described, and for the purpose of facilitating the fastening of a skate upon the foot, as set forth.
3. A curved self-locking skate-buckle, such as described and shown, as a new article of manufacture.

HALSEY B. LUCAS.
